FIG. 1-.

This technical drawing illustrates a cross-sectional view of a mechanical assembly. On the left, a cylindrical component 33 is shown with a flange 32. A curved tube 26 is connected to the flange 32. A vertical rod 25 extends from the tube 26. A lever arm 36 is attached to the rod 25. A circular component 29 is mounted on the lever arm 36. A vertical slot 11 is visible on the side of the lever arm 36. A vertical wall 14 is on the right. A vertical cylinder 20 is positioned on the right side. A piston 15 is located within the cylinder 20. A rod 18 is connected to the piston 15. A vertical tube 39 is connected to the cylinder 20. A piston rod 21 is connected to the piston 15. A piston 17 is located within the piston rod 21. A piston rod 23 is connected to the piston 17. A piston 24 is located within the piston rod 23. A piston rod 22 is connected to the piston 24. A piston 21' is located within the piston rod 22. A piston rod 21'' is connected to the piston 21'. A piston 21''' is located within the piston rod 21''. A piston rod 21'''' is connected to the piston 21'''.

Technical drawing of a mechanical assembly, likely a valve or pump component, showing internal parts labeled 20 through 40 and 35, 37, 38, and 39. The drawing is signed "D. Kendall" at the bottom right.

UNITED STATES PATENT OFFICE

DOUGLAS KENDALL AND DON HEYER, OF HOLLYWOOD, CALIFORNIA

EXERCISING MACHINE

Application filed June 27, 1929. Serial No. 374,304.

This invention relates to new and useful improvements in exercising machines, and particularly to reducing machines.

One object of the invention is to provide an exercising machine of this character which is especially adapted for producing body vibrations of the patient in a manner simulating rolling.

Another object is to provide a device of this character by means of which the patient may be vibrated, upon grasping and holding certain parts of the machine.

A further object is to provide a device of this character wherein the patient may cause his body to be vibrated, after the manner of rolling, and at the same time cause his body to be further vibrated by grasping certain parts of the machine.

Other objects and advantages will be apparent from the following description when taken in connection with the accompanying drawings.

In the drawings:

Figure 1 is a side elevation of an exercising machine made in accordance with the present invention.

Figure 2 is a top plan view of the same.

Figure 3 is a vertical longitudinal sectional view on the line 3—3 of Figure 2.

Figure 4 is a vertical transverse sectional view on the line 4—4 of Figure 2.

Figure 5 is an end view of the device showing the member 29 in elevation.

Figure 6 is a detail view of one of the handles 32, showing the cover in section.

Figure 7 is a fragmentary view showing one end of the strap 38.

Referring particularly to the accompanying drawings, 10 represents a suitable base which is adapted to be attached to a support, such as a table top 11, by means of the screw 12, such base having openings for receiving the bolts 13 for attaching the various devices thereto.

Properly mounted on the base 10, adjacent one end, is an electric motor 14, one end of the shaft 15, of which, is provided with a grooved pulley 16. Mounted on the base, adjacent the pulley 16, is a bearing bracket 17, in which is supported the shaft 18, which ex-

tends longitudinally of the base, and in a plane parallel with the shaft of the motor, said shaft having a grooved pulley 19 mounted on one end, which alines with the pulley 16 so as to be driven from the motor by the belt 20, bearing balls 21 being properly arranged within the bracket for the shaft 18. On the other end of the shaft 18 there is formed an eccentrically arranged crank pin 21', and engaged thereon is one end of a pitman rod 22, suitable bearings 23 being properly arranged between the crank pin and rod end.

Rising from the center of the end of the base, opposite to that on which the motor is mounted, is a post 24, which is hollow and has slots 25 in opposite sides. Disposed within this hollow post is a vertical shaft 26, adapted to rock therein, as will be later described herein. Disposed on the vertical shaft 26 is one end of a stem 27, a shaft 28 being disposed through the vertical shaft 26, and into the stem 27. This portion of the stem 27 which is mounted on the vertical shaft 26 is disposed for movement in the slots 25, as well as the end portions of said shaft 28, to permit the stem to be rocked laterally. Formed on the other end of the stem 27 is a transverse portion, indicated as a whole by the numeral 29, the outer face of which is divided into two convex portions 30, which incline inwardly toward the adjacent end of the stem, such portions having their outer faces partially scored, as at 31. Formed on the member 29, at each side of the stem 27, and inclining upwardly and inwardly toward the post 24, is a stud 32, on which is removably disposed a rubber hand-grip 33.

Connected to the inner end of the shaft 28 is the other end of the pitman rod 22, a self-aligning bearing 34 being of the type shown in the U. S. Patent #1,400,754, arranged between the shaft and said rod end. Removably engaged on the said end of the shaft 28, inwardly of the connection of the pitman, is a heavy block 35, which serves as a counterbalance for the rocker member 29. On each end of the portion 29, is a headed stem, or button, 36, which is adapted to be received in the buttonhole 37, on the end of the strap 38.

A cover 39 is arranged over the mechanism

on the base, such cover being properly attached to the base by the screws 40, and having an opening 41, in one end, through which the stem 27 is adapted to move, during the 5 operation of the device.

In one use of the device, the patient stands in a position facing the member 29, the ends of the strap 38 being properly engaged with the buttons 36, and the intermediate portion 10 thereof engaged around the rear of the patient, at approximately the waistline. The motor is then started, and the patient leans back until he rests against the strap. The 15 rocking of the member 29 will alternately pull the ends of the strap, with the result that the patient will be vibrated after the manner of rolling. The more pressure the patient exerts against the strap, the stronger will be the vibrations to his body.

20 Another manner of use of the device is for the patient to place his abdomen against the convex faces 30, so that a patting massaging action will be accomplished. If the patient desires, he may grasp the handles 33, at the 25 same time that the members 30 operate against the abdomen, so that the arms will transmit a vibratory motion to the upper portion of his body. He may also grasp these handles while using the strap, with a similar 30 result.

Thus the patient can alternate between the members 30 and the strap 38, whereby to massage the abdomen, and then massage the back. In each instance the arms, shoulders, 35 and upper portions of the body of the patient will be subjected to vibration, through the medium of the handles 33.

What is claimed is:

In an exercising machine, a laterally 40 swingable oscillator having abdomen engaging members on one end and a counterbalance on the other end, a motor having a shaft, a shaft counter to the shaft of the motor, driving connections between the motor and 45 the counter-shaft, and a pitman eccentrically connected with the counter-shaft and operatively connected with the counterbalance end of the oscillator.

50 In testimony whereof, we affix our signatures.

DOUGLAS KENDALL.
DON HEYER.
